UNITED STATES PATENT OFFICE

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY

WORKTABLE GUIDE FOR SHAPING MACHINES

Application filed November 23, 1929. Serial No. 409,287.

This invention relates to work-table guides for shaping machines and it constitutes an improvement over the construction forming the subject matter of my United States patent application Serial No. 229,542 filed October 29, 1927, which has matured into Patent No. 1,753,143 dated April 1, 1930.

An object of this invention is to provide a work-table guide or "cross-rail" as they are commonly called, which will more rigidly support the work-table than will any heretofore provided.

A further object is to provide a work-table guide which will have all of the advantages of the construction disclosed in said application and which will afford the additional advantages of having fewer bearing surfaces and which therefore will be easier and less expensive to build.

Another object is to provide a cross-rail in which, by a single adjustment, all play may be taken up between the various complementary bearing surfaces of the cross-rail and the work-table slidingly mounted thereon.

Still another object is to provide a cross-rail in which adjustment between the bearing surfaces of the cross-rail and work-table may be effected differentially at opposite ends of the cross-rail, thereby to compensate for unequal wearing of the surfaces due, for example, to continued use of the shaper with the table adjacent one end of the rail.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is a partial side elevation of a shaping machine embodying a preferred form of my invention. Fig. 2 is a left end elevation of Fig. 1. Fig. 3 is an enlarged cross-sectional view of my improved cross-

rail and complementary work-table fitted thereto. Fig. 4 is a detail sectional view showing a first modified construction adapted to afford the desired adjustments and Fig. 5 is a detail sectional view illustrating a second modified form.

Referring more specifically to the drawings, the invention is illustrated as embodied in a shaping machine comprising a base 1, frame 2, reciprocating tool-carrying ram 3 and a horizontal cross-rail or table guide 4 upon which is slidingly supported a work-table T. The cross-rail is vertically adjustable on the frame 2, such adjustment preferably being effected by a screw 6 and a co-operating nut 7, one of which is adapted to be rotated relative to the other. Clamp bolts 8, carried by the cross-rail and projecting through slots 9 formed in bearing plates 10 provided by the machine frame, and through a clamp plate 11, are fitted with nuts 12 which co-operate with the bolts to clamp and securely lock the cross-rail to the frame in all of its vertical positions. The work-table may comprise a single casting and have bearing surfaces fitted to the bearing surfaces of the cross-rail but preferably, for convenience of manufacture and assembling, it will be made in two pieces, one the work supporting portion 5 and the other a saddle 13, secured to the portion 5 as illustrated in dotted lines in Fig. 3, and providing the bearing surfaces complementary to those of the cross-rail.

To enable the work-table to be fed horizontally along the cross-rail a feed screw 14 is journaled lengthwise in the cross-rail and this screw has a threaded connection with a nut 15 fixed to the work-table. Either manual or power means, or both, may be provided for effecting relative rotation between the feed screw and its co-operating nut. In the drawings the feed screw is shown as having one end squared, as at 16, to receive a conventional hand crank.

The improved cross-rail is preferably made as a casting and is suitably ribbed and cored to provide the required strength with a minimum amount of weight. The cross-rail comprises a rear wall 17 having bearing surfaces fitted to vertically disposed guideways pro-

vided by the frame 2, a forwardly projecting wall or portion 19 at its upper edge, and a forwardly projecting wall 20 at its lower edge. Intermediate its edges the cross-rail

5 is provided with forwardly projecting portion 21 substantially rectangular in cross section, which for convenience hereinafter will be referred to as a ledge or ledge member.

This member provides, at its upper face, a 10 relative wide bearing surface or seat 22 which sustains the weight of the work-table. The forward face 23 of the ledge member 21 also is finished and forms a thrust bearing surface to prevent inward movement of the upper portion of the table.

15 Extending upwardly from the lower horizontal wall 20, and formed integral therewith, is a vertically disposed wall 24 affording at its front face a bearing surface 25 constituting a thrust bearing

20 ing for preventing inward movement of the lower portion of the work-table. The upper portion of the wall 24 is connected with the rear wall 17 by a transverse wall 26. The walls 17, 19, 20, 24 and 26 and the ledge mem-

25 ber 21 extend the full length of the cross-rail and are all integral, being connected together at their ends by end walls 27 and 28.

In the preferred embodiment of the invention the forwardly projecting portion 19 has 30 adjustably secured to it a substantially L-shaped bar or strap member 29 having a lower upwardly and rearwardly inclined bearing face 30 arranged preferably at about thirty-five degrees from the horizontal.

35 This strap is adjustable vertically by means of adjusting screws 31 threaded through the portion 19 and bearing upon the lateral portion 29 of said strap. Clamp screws 32, passing freely through enlarged openings in the strap and threaded into the portion 19, serve rigidly to secure the strap to the portion 19 in all of the adjusted positions of the strap.

The table T is provided with finished bearing surfaces 33 and 34 adapted to engage the surfaces 23 and 25 of the cross-rail, thereby to prevent inward movement of the top and bottom portions, respectively, of the table.

40 A rearward extension 35, of the table, is provided with a horizontal bearing surface 36 adapted to rest upon the seat 22 provided by the ledge member 21 whereby the entire weight of the table is carried by said member.

The extension 35 also is provided, at its upper face, with an inclined bearing surface 37 engaging the bearing face 30 of the strap 29.

45 During operation of the shaper, due to the overhang of the table and the action of the tool on the work, the forward end of the table tends to swing outwardly and downwardly about the point f which acts as a fulcrum. Portions of the table located rearwardly of the fulcrum point tend to move upwardly and outwardly. If permitted to

50 yield to those stresses the rear edge of the table would assume a position somewhat as

indicated by dot-dash lines d in Fig. 3. However, with the improved cross-rail all inward, outward, upward and downward movement of the table is positively prevented. The strap 29 performs the dual function of holding the upper portion of the table against upward and outward movement.

From the foregoing it will be perceived that in the present cross-rail, only four table bearing surfaces are required to be finished to wit:—surfaces 22, 23, 25 and 30. Inasmuch as the finishing of such bearing surfaces is a decidedly expensive operation, requiring many hours of hand scraping, it will be apparent that any reduction in the number of surfaces will result in a corresponding reduction in the cost of manufacture. This invention has not only reduced the cost of manufacture but at the same time has produced a structure which will better resist the strains to which the cross-rail is subjected. This latter is due partly to the fact that the lever arm between the fulcrum f and the inclined bearing surface which takes the upward and outward thrust is substantially longer than in prior constructions, said bearing, in the present construction, being placed at the upper part of the cross-rail above the table seat instead of beneath the table seat adjacent the central portion of the cross-rail as in prior constructions. As hereinbefore stated, vertical adjustment of the strap 29 compensates for wear on the bearing surfaces 23, 33—22, 36 and 30, 37. An important feature of this invention resides in the ability of the strap to be adjusted differentially at its opposite ends thereby to compensate for uneven wear on the bearing surfaces due to continued use of the machine with the table adjacent one end of the cross-rail. In the preferred construction the differential adjustment is effected by individual adjustment of the screws 31.

In prior shaping machines no means was provided for adjusting the bearings differently at their opposite ends and therefore difficulty was experienced when the bearings had become worn more at one end of the cross-rail than at the other inasmuch as adjustment to take up the play in the end having the greater wear would cause binding at the end having the lesser wear.

55 In the modified construction shown in Fig. 4, play between the bearing surfaces is taken up by horizontal adjustment of the strap 29. To that end shims s are initially placed between the strap and the portion 19 of the cross-rail when the machine is built and are removed as required to permit the strap to be adjusted inwardly by the bolts 32.

Fig. 5 illustrates a second modification in which the overhanging portion 19^a of the cross-rail, corresponding to the portion 19 of Fig. 1, and the downwardly extending portion 39, corresponding to the strap 29, are

formed integral. In this construction adjustment to take up wear between the bearing surfaces is effected by an endwise movable 5 tapered gib 38 inserted between the overhanging and downwardly extending portion 39 of the cross-rail and the portion 40 of the table. This construction, however, does not admit of differential adjustment to compensate for unequal wear as do the forms shown 10 in Figs. 1 and 4.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore such adaptations 20 should be, and are intended to be, comprehended within the meaning and range of equivalency of the following claims:

Having thus revealed this invention, I claim as new and desire to secure the following combinations and elements, or equivalents thereof, by Letters Patent of the United States:

1. A shaper combining a frame, a cross-rail mounted thereon and affording a relatively wide horizontal disposed table-supporting seat; a work-table translatable mounted on said cross-rail and having a lateral extension fitted to said seat, said extension being provided, above said seat, with an upwardly and rearwardly inclined bearing surface; a portion of said cross-rail projecting forwardly over the extension of said work-table and having an upwardly and rearwardly inclined bearing surface contacting with the first named bearing surface solely to hold said work-table against upward and outward movement.

2. A shaper combining a frame; a cross-rail mounted thereon and affording a relatively wide horizontally disposed table-supporting seat; a work-table fitted to said seat and supported thereby, said work-table being provided, above said seat, with an upwardly and rearwardly inclined bearing surface, and a portion of said cross-rail overlying said seat and having a bearing surface in contact with the first named bearing surface to hold said table against upward and outward movement relative to said seat.

3. A machine tool combining a frame; a cross-rail supported thereon; a member fitted to and translatable mounted on said cross-rail, said cross-rail providing a horizontally disposed seat for supporting the weight of said member, a vertical bearing surface to prevent movement of said member toward said cross-rail, and a portion overlying said seat and providing a single bearing surface to prevent upward and outward movement of said member relative to said

seat, the bearing surfaces of said cross-rail engaging complementary bearing surfaces on said translatable member.

4. A shaper combining a frame; a cross-rail mounted thereon; a work-table translatable mounted on said cross-rail; a feed-screw journaled in said cross-rail; a feed nut supported by said table and engaging said screw; a ledge member provided by said cross-rail, said ledge member being located 70 above said feed screw and affording a vertical bearing surface and a relatively wide horizontal seat; a second vertical bearing surface provided by said cross-rail below said feed-screw, said work-table being supported by said seat and held against movement toward said cross-rail by said vertical bearing surfaces, said work-table having above said table-seat an inclined bearing surface; and a portion of said cross-rail overhanging said inclined bearing surface and engaging the same to prevent upward and outward movement of said table.

5. A shaper combining a frame; a cross-rail mounted thereon and affording a relatively wide horizontally disposed table-supporting seat; a work-table translatable mounted on said cross-rail and having a lateral extension fitted to said seat, said lateral extension being provided above said seat with an upwardly and rearwardly inclined bearing surface; a member adjustably secured to said cross-rail above said extension and having an upwardly and rearwardly inclined bearing surface contacting with the first named bearing surface to prevent upward and outward movement of said table; means to adjust said member to compensate for wear on said bearing surfaces; and a thrust bearing provided by said cross-rail and engaging the lower portion of the cross-table 100 to prevent inward movement of the lower portion of the table.

6. A shaper combining a frame; a cross-rail mounted thereon said cross-rail comprising a vertically disposed thrust bearing wall at its lower edge, a horizontally disposed seat above its center line and a forwardly projecting portion at its upper edge; a work-table supported upon said seat and having a portion abutting said thrust bearing, said table also having a portion underlying the forwardly projecting portion of said cross-rail, said underlying portion of the table 110 being formed with an upwardly and rearwardly inclined bearing surface, a strap adjustably supported on the forwardly projecting portion of said cross-rail, said strap having an inclined bearing surface in overlying contact with the first mentioned inclined bearing surface; adjusting screws threaded through the forwardly projecting portion of said cross-rail and engaging said strap to adjust the strap thereby to force 115 said inclined bearing surfaces together; and

clamp screws engaging said strap to lock it in its adjusted positions.

7. A shaper combining a frame; a cross-rail supported thereby; said cross-rail providing a vertical bearing surface adjacent its lower edge and a horizontal seat above the center line thereof, a work-table supported upon said seat and abutting against said vertical bearing surface; and a portion 10 of said cross-rail hooking over and engaging an upwardly and rearwardly inclined bearing surface provided by said work-table above said seat, for holding said table against upward and outward movement.
16. 8. A shaper combining a frame; a cross-rail mounted thereon and affording a horizontally disposed table supporting seat; a work-table translatable mounted on said cross-rail and supported by said seat, said 20 table being provided above said seat with an upwardly and rearwardly inclined bearing surface; a member substantially co-extensive with said cross-rail and adjustably secured thereto above said seat and having 25 an upwardly and rearwardly inclined bearing surface contacting with the first named bearing surface to prevent upward and outward movement of said table; and means to adjust said member differentially to compensate for unequal wear on said bearing surfaces.

In witness whereof, I have hereunto subscribed my name.

WILLIAM F. ZIMMERMANN.
